UNITED STATES PATENT OFFICE

FRANK KAHL, OF RICHMOND, VIRGINIA.

IMPROVEMENT IN FLEXIBLE VALVES.

Specification forming part of Letters Patent No. 171,817, dated January 4, 1876; application filed November 15, 1875.

To all whom it may concern:

Be it known that I, FRANK KAHL, of the city of Richmond, in the county of Henrico and State of Virginia, have invented certain new and useful Improvements in Valves, of which the following is a specification:

My invention relates to that class of valves particularly applicable to the pumping of semi-liquids, or liquids in which solid substances are encountered, such as wood, ashes, stones, &c., ordinarily found in privy-vaults, cess-pools, &c., or solid substances found in the bilge-water of vessels, though the valve is applicable to general use as a check or stop valve; and consists in a flexible casing so arranged that a portion of it forms flaps or lips at the eduction-port of the valve of comparatively contracted superficial area, said flaps or lips to close and guard said port by bringing into close contact one of the faces of said casing, with its coinciding face, by reason of its angle of inclination, this action being aided by a hinged weighted cover; and the invention further consists in a metallic seat composed of two metallic casings, or of two casings made of any other suitable material, said casings forming between them a space for the insertion of the flexible casing, these metallic or other casings being so constructed that when the valve is closed the faces of the flexible casing shall lie in a plane oblique to the plane of the seat, and form, when the valve is open, a smooth and unobstructed passage of practically the same diameter throughout, the greater portion of which is lined with metal, thereby reducing the frictional contact of the matter passing through the valve, with the walls thereof, as well as reducing the wear of the flexible casing to a minimum; but,

That my invention may be fully understood, I will proceed to describe the same in detail by aid of the accompanying drawings, in which—

Figure 1 is a perspective view of a valve constructed according to my invention. Figs. 2 and 3 are longitudinal and transverse sections through lines $x x$ and $y y$ of Fig. 1; and Fig. 4 is a perspective view of the flexible casing.

The valve belongs to that class having a hinged weighted cover, and consists of a seat,

A , formed or composed of two metallic casings, $a a'$, one within the other, and so connected as to form between them an aperture or trough for the reception of the flexible casing D . The induction-port of the seat is formed square, but may be of tubular shape, if preferred, though in practice, and for the particular purposes to which the valve is adapted, I prefer to adopt the square form, as shown. The sides of the seat are inclined at an angle oblique to the plane of the fluid-passage, or horizontal portion of the seat, which is extended or projected some distance beyond the base of the incline. The bed-plate of the inner metallic casing is shorter than that of the outer one, and the latter has no top plate at the induction or square end, so that the flexible casing may be secured in position in the trough or space between such casings by means of the clamp C , or any other suitable or preferred means. The inner casing a' is provided with suitable means to connect the same to the piston or the pump chamber, and is connected with the outer casing in any usual or preferred manner. D is the flexible casing, of a tubular shape, or of a shape to correspond with that of the metallic seat, and adapted to fit into the trough formed by the two casings of such seat. It may be made of canvas, leather, or rubber, or any other flexible material, either tubular or pressed into shape, the latter of which I prefer, and the material I have found best for the purpose is rubber. The form of this casing is fully illustrated by Fig. 4 of the drawings. This flexible casing is inserted in the trough formed by the two metallic casings of the seat, and clamped in position, as described. It is further secured by riveting it or otherwise securing it to the inner shorter and outer longer horizontal floors of the seat, thereby reducing the frictional contact of the substances passing through the valve, with its walls and those of the flexible casing, and consequently reducing the wear of the valve to its minimum. The outer end of the seat, from the base of the incline, is slightly curved upward, so that the inclined face of the flexible casing shall come in contact with its coincident face in a plane not at right angles to the plane of the valve-opening. By this means the area of contact is reduced to an

extent just sufficient to form a tight joint between the faces, or between them and any solid substance that may remain in the education-opening, as it has been amply proven by experience that the more the area of contact is reduced the more perfect is the joint.

The flexible casing D is longer than the seat, so as to project a short distance beyond the seat, to form lips or flaps of comparatively contracted or small superficial area, which, when the valve is closed, owing to their elasticity or flexibility, will readily adapt themselves to the configuration of any solid substance of such a length as not to have been passed through the valve by the lifting stroke of the pump, and form a close contact around such substance, and thus enable the valve to perform its functions. B is the weighted hinged cover, riveted, or otherwise secured, to the free or inclined face of the flexible casing. This cover extends from a point at the upper edge of the incline of the seat (which point it overlaps slightly in the direction of the induction-port) to the lower edge of the incline, and is gradually increased in thickness toward that point, from whence it is slightly curved upward to coincide with the form of the seat, and terminates within a short distance of such seat, which extremity is also its thickest or heaviest portion. This cover aids in bringing the inclined face of the flexible casing into valve contact with the coincident face of said casing at the lip or flap portion thereof, over an area just sufficient to effectually close the valve, and cause the lips to close around any solid substance that may not have had time to pass through the valve. The bearing of the weighted metallic hinged cover upon the seat of the valves is not essential to bring the coincident faces of the flexible casing into valve contact, as this contact is formed at the flap or lip end of the valve, by reason of the angle of inclination of the sides of the seat, and that of the flexible casing, in relation to the plane of the valve-passage.

It is evident, therefore, that should any solid substance remain in the valve at the point of contact of the lips or flaps of the flexible casing, such lips or flaps, owing to their flexibility or elasticity, will effectually close around such substance, by adapting themselves to the shape of it, and thus form a valve-joint. The passage throughout the

valve being smooth and unobstructed, and practically of the same diameter throughout, it is an impossibility for any such solid substance to become lodged or wedged therein, and choke the valve or prevent it from closing perfectly.

The cover also serves the purpose of protecting the outer face of the flexible casing, and preventing the same from being forced into the valve-opening by the pressure.

Having now described my invention, what I claim, and desire to secure by Letters Patent, is—

1. In a valve, the flexible casing, having its roof inclined oblique to its base to close and guard the valve-port, and so arranged as to form flaps or lips of contracted superficial area, the coincident faces of which shall engage in close contact at their outer extremities only, substantially as and for the purposes specified.

2. In a valve, the combination with the seat, constructed substantially as described, of a flexible casing, forming flaps or lips, so arranged that the coincident faces thereof, shall engage in close contact at an angle oblique to the plane of the induction-port, whereby said contact is effected at the outer extremities only, of such flaps or lips, and over a minimum superficial area, substantially as and for the purposes set forth.

3. A valve, consisting of a double metallic seat, forming a casing, and having its sides inclined for the purpose set forth, in combination with the flexible casing, when arranged to operate as and for the purposes described.

4. The combination of a weighted cover, constructed substantially as specified, with the flexible casing so arranged as to form valve flaps or lips of comparatively contracted superficial area, substantially as and for the purposes specified.

5. The combination of a double metallic seat, with a flexible casing and a weighted metallic cover, substantially as and for the purposes described.

In witness that I claim the foregoing I have hereunto set my hand this 13th day of November, 1875.

FRANK KAHL.
